DISPOSABLE HEADDRESS UNIT

Gilbert B. Wagenfeld, Philadelphia, Pa.

Application March 20, 1956, Serial No. 572,734

5 Claims. (Cl. 2—209.3)

This invention relates generally to headgear of the type generally worn by waitresses and more particularly to a novel construction of a headdress formed of a single blank of flat sheet material.

Among the principal objects of the present invention is to provide a headdress which is adapted to be produced of a single blank of flat sheet material which is so die-cut and scored that it may be quickly and easily set up into shape to be worn and which includes means not only for securely holding the blank to its predetermined headdress shape but also for securing it in position upon the head of the wearer.

A further object of the invention is to provide a headdress which is of pleasing design and appearance and of such inexpensive construction that it may be discarded after reasonable use at a negligible replacement cost.

Still another and more specific object of the invention is to provide a headdress which includes as an integral part thereof a set of comb-like teeth adapted to be inserted into the hair of the wearer of the headdress to firmly secure it in wearing position upon the head.

Still further, it is an object of the present invention to provide a headdress formed of a single blank of sheet material which is die-cut and scored to facilitate its being set up into shape and which includes interlocking relatively foldable parts which are operative to securely hold the blank into its shaped headdress form.

Other objects and advantages of the invention, including those relating to economies of manufacture, will appear more fully hereinafter, it being understood that the present invention consists substantially in the combination, construction, location and relative arrangement of parts, as described in detail in the following specification, as shown in the accompanying drawings and as finally pointed out in the appended claims.

In the accompanying drawings:

Figure 1 is a perspective view showing the headdress of the present invention as it appears when worn upon the head;

Figure 2 is a sectional view of the headdress as taken along the line 2—2 of Figure 4;

Figure 3 is a sectional view of the headdress as taken along the line 3—3 of Figure 2;

Figures 4 and 5 are front and rear views of the headdress as viewed respectively from the lines 4—4 and 5—5 of Figure 2; and

Figure 6 is a plan view of the blank of which the headdress is formed.

Referring now more particularly to the drawings, it will be observed that the headdress of the present invention, designated generally by the reference numeral 10, comprises a one-piece, unitary structure formed of a single blank 11 of flat sheet material which is cut to shape and scored as shown in Figure 6. This blank may be suitably formed of cardboard, chip-board, vulcanized fiber, plastic or any other flexible sheet material having an inherent stiffness or rigidity sufficient to main-

2

tain the headdress in its predetermined form and contour when the blank is set up ready to be worn.

The blank 11, which is advantageously die-cut from a flat sheet of any suitable material as above mentioned, 5 essentially constitutes a main body or crown portion 12 of generally crescent shape the upper marginal edge 13 of which may be provided with a central upwardly presenting peak portion 14 to ornament and enhance the appearance of the headdress unit. Extending transversely across the bottom of the crescent-shaped crown portion 12 of the blank is a coplanar strip 15, the inner edge 16 of which is spaced from the curved bottom edge 17 of the crown portion by a die-cut opening 18. The strip 15, which thus interconnects the opposite horns or pointed end portions of the crescent-shaped crown piece 12, is centrally enlarged, as at 19, by laterally extending the central portion of the strip 15 somewhat beyond its outer edge 20.

The opposite end portions of the strip 15 are each 20 provided with a set of comb-like teeth 21 which are die-cut to their desired shape and spaced relation and which project outwardly of the strip 15 in the plane of the blank.

The lines of juncture between the opposite ends of the strip 15 and the crescent-shaped crown piece or main body portion 12 of the blank are respectively scored, as at 25 22—22, while the strip 15 is itself scored within the area immediately adjoining the inner end of each set of the teeth 21 along a pair of spaced parallel lines 23 and 24.

30 It will be noted that the score lines 23 and 24 adjacent the inner end of a given set of teeth 21 are reversely inclined with respect to the score line 21 adjacent the outer end of said given set of teeth, and that the outer lines of scoring 22—22 and the inner lines of scoring 35 23—23 and 24—24 are such as to favor bending of the strip 15 angularly with respect to the body portion 12 of the blank into its relative position shown in Figures 2 to 5, inclusive.

40 The permissible bending of the strip 15 relatively to the crown or body portion 12 of the blank is such as to present the central enlarged portion 19 of the strip in flatwise engagement with the inner surface of the crown piece 12 immediately adjacent its curved bottom edge 17 and the inner edge 16 of the strip 15 in close proximity to the said curved bottom edge of the crown piece 17.

Upon thus bending the strip 15 relatively to the crown piece so as to present the portion 19 of the strip flatwise against the inner surface of the crown piece 12, the opposite end portions of the latter are drawn inwardly out 50 of the flat plane of the blank, in consequence of which the crown piece 12 transversely assumes a generally bowed shape, as shown in Figures 1, 2, 4 and 5. At the same time, and because only the central portion 19 of the strip 15 is disposed flatwise against the inner surface of the crown piece, the comb-like teeth 21 at opposite ends of the strip 15 are disposed in a plane which extends substantially at right angles to the crown piece 12, as seen in Figure 3.

60 Any suitable means may be employed to secure the central portion 19 of the strip 15 flatwise against the crown piece to retain the latter in its shape to be worn as a headdress. Thus, the portion 19 may be cemented or otherwise adhesively secured to the crown piece or it may be pinned, stitched or stapled thereto. Preferably, 65 however, the strip 15 is releasably secured to the crown piece 12 by interlocking tongue and slot means formed respectively as integral elements of the strip 15 and the crown piece 12. Thus, as shown in Figure 6, the blank 11 may be provided in its crown piece portion 12 with a pair of spaced, parallel slits 25—25, while the strip 15 is in turn provided with a tongue part 26 which is adapted to be inserted through the slits 25—25, as shown in Fig-

ures 2 and 4, to releasably interlock the strip portion 19 flatwise against the inner surface of the crown piece. Thus, the headdress units may be supplied to the user in the form of flat die-cut blanks and then set up as needed into headdress shape ready for use. Should it be found necessary to store a quantity of the headdress which had been but are temporarily not in use, the set up units may be returned to flat form by the simple expedient of disengaging the tongue and slot connection which holds the headdress in shape to be worn.

It will be apparent, of course, that the comb-like teeth 21 at either side of the headdress are adapted to be projected into the hair of the wearer and thus serve to effectively hold the headdress firmly in position upon the head. It will be noted also that the two sets of teeth are relatively so disposed that when the headdress is set up into shape, the teeth on one side of the wearer's head present toward those on the opposite side, in consequence of which the two sets of teeth operate conjointly to lock the headdress into the hair of the wearer, thus dispensing entirely with the necessity of tying or otherwise securing the headdress in position.

It will be understood, of course, that the present invention is susceptible of various changes and modifications which may be made from time to time without departing from the general principles or real spirit of the invention, and that it is accordingly intended to claim the same broadly as well as specifically, as indicated by the appended claims.

What is claimed as new and useful is:

1. A head-dress unit comprising a single blank of sheet material cut and scored to provide a crescent-shaped main body portion constituting the crown piece of the head-dress and an integral strip extending transversely between and interconnecting the opposite pointed extremities of the crown piece, said blank being scored to provide downwardly diverging fold lines respectively disposed between the opposite extremities of the crown piece and the opposite ends of said transversely extending strip, said blank being centrally cut out to provide the crescent-shaped main body portion with a curved bottom edge spaced from the proximate inner edge of said transversely extending strip and extending between and merging with said diverging score lines, whereby said strip is bendable out of the flat plane of the blank to present the central portion of said strip flatwise against the back surface of the crown piece with the inner edge of the strip in substantial coincidence with the bottom edge of the crown piece and thus cause said crown piece to assume a transversely bowed shape.

2. A head-dress unit comprising a single blank of sheet material cut and scored to provide a crescent-shaped crown piece section having a curved bottom edge and a strip extending chordally across the bottom of said crown piece section with its inner edge spaced from the curved bottom edge of the crown piece section, said blank being

scored to provide a pair of fold lines respectively extending downwardly and outwardly from the opposite ends of the curved bottom edge of the crown piece section to the outer edges of the blank, said chordal strip being bendable out of the flat plane of the blank along said score lines to present the central portion thereof flat against the back surface of the crown piece section with the inner edge of the chordal strip and the curved bottom edge of the crown piece section in substantial registry to thereby cause the crown piece portion to assume a transversely bowed shape, and means for securing said central portion of the chordal strip in position flatwise against the back surface of the crown piece section for retaining the latter in position to be worn as a head-dress.

15 3. A head-dress unit comprising a single blank of sheet material cut and scored to provide a crescent-shaped crown piece section having a curved bottom edge and a strip extending chordally across the bottom of said crown piece section with its inner edge spaced from the curved bottom edge of the crown piece section, said blank being scored to provide a pair of fold lines respectively extending downwardly and outwardly from the opposite ends of the curved bottom edge of the crown piece section to the outer edges of the blank, said chordal strip being bendable out of the flat plane of the blank along said score lines to present the central portion thereof flat against the back surface of the crown piece section with the inner edge of the chordal strip and the curved bottom edge of the crown piece section in substantial registry to thereby cause the crown piece portion to assume a transversely bowed shape, and a plurality of comb-like teeth formed integrally with said chordal strip and being bendable with the latter for disposition in a plane substantially coincident with and extending at an angle to the bottom curved edge of the crown piece section, said teeth being adapted to project rearwardly of the bowed crown piece section for engagement with the hair of the wearer of the head-dress.

40 4. In a head-dress unit as defined in claim 3 wherein said comb-like teeth are arranged in laterally spaced sets respectively located adjacent opposite ends of the crown piece section.

45 5. In a head-dress unit as defined in claim 3 wherein said chordal strip and said crown piece section are respectively provided with coacting means for releasably interlocking the same together.
